MASON'S GUIDE LINE HOLDER OR SIMILAR ARTICLE

Harry Donald Stone, Uniontown, Pa., assignor to Summit Products Company, Uniontown, Pa., a partnership

Filed Feb. 25, 1964, Ser. No. 78,771

Term of patent 14 years

(Cl. D51—1)

FIG. 1

FIG. 2

FIG. 3

FIG. 5

FIGURE 1 is a perspective view of a mason's guide line holder or similar article showing my design;

I claim:

The ornamental design for a mason's guide line holder or similar article, as shown.
